UNITED STATES PATENT OFFICE.

HARRY SWINGLEHURST, OF BOSTON, MASSACHUSETTS, ASSIGNOR TO SCOTT & WILLIAMS, INCORPORATED, OF CAMDEN, NEW JERSEY, A CORPORATION OF NEW JERSEY.

*KNITTING-MACHINE CYLINDER.

1,115,129.

Specification of Letters Patent. Patented Oct. 27, 1914.

Application filed March 27, 1912. Serial No. 686,583.

To all whom it may concern:

Be it known that I, HARRY SWINGLEHURST, a citizen of the United States, residing in Boston, Massachusetts, have invented certain Improvements in Knitting-Machine Cylinders, of which the following is a specification.

My invention relates to that type of knitting machine needle cylinders which have inserted strips projecting from the periphery of the cylinder so as to form walls between which are the grooves for the guidance of the needles, the object of my invention being to so construct such a cylinder as to limit the lateral play of the needles in the grooves.

In the accompanying drawing Figure 1 is a sectional plan view of part of an ordinary inserted wall cylinder for knitting machines illustrating the objection thereto which my invention is intended to overcome. Figs. 2 and 3 are similar views illustrating embodiments of my invention, and Fig. 4 is a perspective view of one of the walls constructed in accordance with my invention.

All of the views of the drawing are on an exaggerated scale, Figs. 1 to 3 being on a larger scale than Fig. 4.

In the drawing, 1 represents part of the needle cylinder which has, in its periphery, properly spaced saw kerfs or milled slots for the reception of the base portions of the walls which are intended to project from the periphery of the cylinder and form between them the grooves for the reception of the knitting needles 2. If these walls are simply parallel-sided strips of steel of uniform thickness, as shown at 3, in Fig. 1, the needle guiding grooves will, owing to the radial disposition of the walls, be wider at their outer ends than at their bases and the needles, being free to assume an angular position in the groove, as shown in Fig. 1, will have a tendency to work out of the grooves, and will not be as effectively supported as if the opposite sides of the needle grooves were parallel.

In carrying out my invention, therefore, I construct the walls as shown in Figs. 2 to 4, the projecting portion 3^a of each wall being beveled on each side, as shown in Fig. 2,

or on one side, as shown in Fig. 3, and being so disposed in respect to a radial line α passing through the center of the needle that the opposite sides of the needle grooves will be parallel with said line. Each of the special walls, therefore, is wider at the outer end than at the portion where it joins the base which is inserted in the slot of the cylinder, the latter retaining its original parallel-sided form so that it will fit snugly in the parallel-sided saw kerf or milled slot formed in the cylinder. By this means if the needle receiving grooves between the walls are of proper width for the needles, any displacement of a needle in its groove is effectively prevented.

I claim:

1. The combination of a knitting machine cylinder having parallel-sided grooves therein with inserted walls projecting beyond the periphery of the cylinder so as to form needle guiding grooves between them, the base portion of each of these walls being parallel-sided and fitting snugly in the corresponding parallel-sided groove of the cylinder, but the projecting portion of the wall being of least width where it joins the base but increasing in width as it extends outwardly from said base, and being of such conformation from end to end of its needle guiding portion, whereby the intervening needle grooves are parallel-sided throughout the needle receiving portions of the same.

2. An inserted wall for a knitting machine cylinder, said wall having a parallel-sided base and a needle guiding portion beyond the base which is of least width where it joins the base and gradually increases in width from the base toward the outer end, the projecting portion of the wall being of such conformation throughout the entire needle guiding portion of the same.

In testimony whereof, I have signed my name to this specification, in the presence of two subscribing witnesses.

HARRY SWINGLEHURST.
